Patented Dec. 29, 1925.

UNITED STATES PATENT OFFICE.

CHARLES J. GUSTAFSON, OF CHICAGO, ILLINOIS, ASSIGNOR TO STROMBERG MOTOR DEVICES COMPANY, OF CHICAGO, ILLINOIS, A CORPORATION OF ILLINOIS.

CARBURETOR.

Application filed February 11, 1918. Serial No. 216,430.

To all whom it may concern:

Be it known that I, CHARLES J. GUSTAFSON, a citizen of the United States, residing at Chicago, in the county of Cook and State 5 of Illinois, have invented a certain new and useful Improvement in Carburetors, of which the following is a full, clear, concise, and exact description, reference being had to the accompanying drawings, forming a 10 part of this specification.

My invention relates to carburetors.

In supplying mixture to an internal combustion engine, it is essential to provide, not only the quantity demanded by the engine 15 for developing the necessary power but to provide the proper quality of mixture to correspond to the conditions of the engine, such as starting, idling, accelerating and running at various speeds.

It is one of the fundamental objects of the present invention to provide means for exercising as wide a range of control over the mixture proportion for all engine conditions 20 as possible. This range of control I effect by a novel combination of air vents or air bleed ports which open into the fuel nozzle. One supply of air which is vented into the fuel stream is controlled by the position 25 of the throttle, and this air supply is preferably arranged so as to reduce the proportion of fuel in the mixture, particularly at certain engine speeds. Another supply of air vented into the fuel stream is dependent on the suction effective at the fuel nozzle, and 30 this air vent is so arranged that a temporary accelerating charge of fuel is obtained with the increases of suction at the nozzle. The quantity of fuel discharged from the nozzle is therefore subject to throttle position and 35 to the suction existing at the nozzle. The two air vents also operate, of course, to compensate for the natural tendency to produce an excessively rich mixture at the higher engine speeds.

In order to explain to those skilled in the art the construction and use of my invention, I shall now describe an embodiment of the same in detail, in connection with the accompanying drawings which form a part of this 45 specification.

Figure 1 is a top plan view of a carburetor embodying my invention;

Figure 2 is a vertical longitudinal section of the same;

Figure 3 is a cross section taken on the line

3—3 of Figure 1, looking in the direction of the arrows;

Figure 4 is a fragmentary sectional view taken on the line 4—4 of Figure 1 looking in the direction of the arrows;

Figure 5 is a front elevational view taken on the right of Figure 1;

Figure 6 is a section taken on the line 6—6 of Figure 1, looking in the direction of the arrows and

Figure 7 is a fragmentary sectional view.

Fig. 8 is a reduced fragmentary sectional view.

The carburetor illustrated in the drawings comprises a horizontal barrel portion 1, which is provided with an outlet 2 having a flange 3 for suitable attachment to the manifold of the engine. A constant level chamber 4, provided with suitable float valve mechanism (not shown), is formed as an integral part of the main barrel or casing 1. The main barrel or casing 1 is provided with an enlarged inlet portion 5 which is connected to an intake elbow 6. The open end of the intake 5 is embraced by the elbow 6 which is provided with a split lug 7 and a bolt 8 for gripping the periphery of the intake 5 so that the elbow 6 may be adjusted in any desired position. The intake elbow 6 has a suitable intake opening 9 and is provided with a butterfly valve 10, controlling the entry of air to the barrel of the carburetor.

The main barrel member 1 contains the main venturi 11 which fits within the side walls of the barrel. A secondary, or smaller, Venturi tube 12 is mounted in the top of the post 13 and has its inner end extending beyond the most restricted portion of the main venturi 11. The upper end of the post 13 has an enlarged head which is bored out to receive the smaller venturi 12, holding it in accurate alignment with the larger venturi 11.

The post 13 is hollow and has an extension below the walls of the enlarged intake 5. This extension 15 is also hollow and has its lower end threaded to receive a correspondingly threaded head 16 which divides the interior into an accelerating well 17 above the head 16 and a primary well 18 below the head 16. The lower end of the primary well 18 is closed by means of the plug 19.

The head 16 has a hollow sleeve 20. This sleeve 20 has a shoulder 21 which engages the restriction formed in the upper end of the bore of the post 13—15. A separate

sleeve 22 spaced from the sleeve 20 sufficient to form a small annular space 23, has a nozzle 24 at its upper end projecting above the end of the sleeve 20. The upper end 6 of the sleeve 20 fits closely around the outside of the nozzle 24 and closes off the opening between the walls of the post 13 and said nozzle, thereby forming an atomizing chamber 25 about said nozzle.

10 It will be noted that the tip of the nozzle 24 extends above the floor of the atomizing chamber to secure an effective atomization of the fuel by the air entering the passageway 63.

15 A plurality of small passages 26 provide communication between the annular space 23 and the atomizing chamber 25. A number of small openings 28 are formed along the side of the sleeve 20, providing communication 20 between the accelerating well 17 and the annular space 23.

The accelerating well 17 communicates with the primary well 18 through a plurality of openings 29 formed through the 23 head 16.

The atomizing chamber 25 communicates by way of a threaded nipple 30 with the opening or nozzle 31 formed in the small venturi 12. This nozzle opening is slightly 33 beyond the most restricted portion of the venturi 12. It will be noted that the threaded nipple is threaded in the upper end of the bore of the post 13, and projects into a recess in the venturi 12, thereby securely 35 holding the parts together.

The primary well communicates by way 40 of a passage 32 through a restriction formed between the valve 33 and the corresponding seat 34 with the space 35, which forms a part of the float chamber and serves to seal the valve opening 34 against the entry of air or leakage of fuel at this point.

The valve 33 is provided with a stem 36 threaded at its upper end through a wall 45 37 on the upper side of the space 35. A knurled head 38 permits adjustment of the valve 33.

It is to be noted that the positioning of the valve 33 is such that a leakage of air 50 past the threaded part of the stem 36 can not vary the proportions of the mixture as this valve is arranged upon the float chamber side of the restriction.

I provide a throttle valve 41 between the 55 outlet 2 and the carbureting chamber 40. This valve is mounted upon a rocker shaft 42 and operated by suitable lever (not shown). An idling nozzle 43 is placed at the left of the throttle 41, this nozzle 60 being supplied with fuel by way of a passage 44 lying within the rib 45 formed upon the outside of the barrel 1 and supplied with air through the opening 95 which extends through the side wall of the venturi 65 11 and the wall of the barrel 1. A suitable

needle valve having the adjusting head 46 controls the flow of air from the interior of the carburetor to the idling jet 43.

The face of the idling jet 43 is depressed slightly below the surface of the bore of 70 the chamber 1 to give a small passageway for air when the throttle valve 41 is otherwise closed and to prevent the opening and closing of the throttle valve 41 from affecting the opening of the jet too sharply. 75

The passageway 44 which supplies fuel to the idling nozzle 43 communicates by way of a diagonal passage 48 with the annular space 49 formed by a groove in the sides of the head 50, which is threaded into the 80 open bore which is drilled down through the boss 51. The head 50 has a hollow stem 52 extending down and engaging a shoulder 53 at the lower end of the bore. The passageway 54 in the stem 52 communicates by 85 way of the radial openings 55 with the annular space 49. At its lower end the passageway 54 communicates by way of the tube 56 with the fuel passageway 32.

The tube 56 has a restriction 57 controlling the maximum flow of fuel to the idling 90 jet.

An annular space 60 is formed between the stem 52 and the side walls of the bore, this annular space communicating at its upper 95 end with an opening 61 to the interior of the casing 1, as indicated at the reference character 62 in Figure 2.

At its lower end, the annular space 60 communicates with the horizontal passageway 63 which leads into chamber 25.

The opening 61 permits air to enter and to pass into the atomizing chamber 25 for the purpose of air bleeding the jet 31. This opening 61 is controlled by a valve 65 which is connected by the stem 66 to a short operating lever 67, mounted on the rocking shaft 42 that controls the throttle 41. The upper end of the lever 67 is bifurcated as is shown in Figure 1 to embrace the valve rod 110 66. The bifurcated ends 68 are rounded and engage a threaded head 69 on the end of the valve rod 66, this head being held in place by means of the lock-nut 70. A spring 96 lies between the valve member 65 and the 115 guiding sleeve 71, which fits into the bore 72 (see Figure 6) in which the valve 65 is guided. This sleeve 71 embraces the stem 66 and forms a guide therefor. The relation between the throttle valve 41 and 120 the bleeder valve 65 is such that when the throttle is in closed position, the bleeder valve 65 is in its maximum open position.

Thus, when the throttle is substantially closed, the air flows in through the opening 125 61 displacing a certain amount of the fuel and reducing the proportions of fuel to air, forming the mixture.

A certain amount of air may be admitted to the atomizing chamber at all times by 130

having a small normally open orifice as shown at 85 in Figure 7 which admits air at all times, chiefly for the purpose of atomizing the fuel in the chamber 25.

5 The accelerating well 17 communicates with atmosphere outside the carburetor by way of the horizontal passageway 75 and the vertical passageway 76 and the graduated or restricted passageway 77 formed in the 10 plug 78 at the top of the passageway 76. (See Figure 6.)

The operation of the device is as follows:

The level of the gasoline in the float chamber 4 normally stands slightly below 15 the opening or nozzle 31 in the secondary venturi 12, as indicated by the dotted line A—B. When it is desired to start the engine, the butterfly valve 10 in the air inlet is closed by a manual adjustment controlled 20 preferably from the dashboard of the vehicle. The engine is then turned over with partial open throttle creating a suction in the manifold and interior of the carburetor, thereby drawing fuel out at the nozzle 31 25 and at the idling nozzle 43. It is to be noticed that when the parts are at rest the passageways heretofore described are all filled with gasoline to the level of the line A—B. Thus, the passageways 63 and 75 contain 30 fuel which is available for starting purposes. As the air inlet is very greatly restricted and as the fuel discharged is in great excess of the air entering at that time, the volatile constituents of the fuel form with the entering air a mixture sufficiently rich to start 35 the engine.

When the engine is idling, the throttle valve 41 is closed (or substantially closed) 40 and fuel is fed at the idling nozzle 43, the velocity of the air being great enough around the lip of the throttle to atomize the fuel thoroughly.

It will be noticed that the air which is drawn past the idling nozzle 43 first passes 45 through the main body of the carburetor, thus passing the main nozzle and the idling nozzle in series. The same is true of the air bleed for the idling nozzle, this air being taken from the inside of the barrel.

50 As soon as the throttle 41 is opened further to increase the speed of the engine, a greater quantity of fuel is drawn at the nozzle 31 and a less quantity at the nozzle 43, relatively. Thus, the function of supplying fuel to form the mixture passes gradually 55 from the idling nozzle 43 to the main nozzle 31.

The arrangement of the double venturi secures a greater suction upon the nozzle 31, 60 thus ensuring the proper discharge even at a relatively low rate of entry of the air.

As the gasoline which is at present supplied on the market consists in a major proportion of hydrocarbons which are not volatile at atmospheric pressure and tempera-

ture, the fuel must be sprayed rather than vaporized and carried into the manifold in the sprayed or atomized form. So long as the throttle is in such position as to restrict the flow of air materially, the suction within the manifold will be substantially high. Under the drop of pressure which prevails at that point, the less volatile hydrocarbons are volatilized and form a better and more workable mixture. To secure the same explosive effect, the mixture, when the fuel is properly vaporized, may be lower in proportion of fuel to air than when the fuel is drawn in substantially at atmospheric pressure in the form of a spray or mist.

For this reason, the air bleeder for the main jet is given a maximum opening when the throttle is closed as this condition of the throttle corresponds with high suction in the manifold.

For accelerating purposes, the well 17 provides a supply of fuel which is drawn upon by increase of suction attended by opening of the throttle 41. During conditions of running, air enters the restricted orifice 77 in the plug 78, passes down through the passageways 76—75, displacing some of the gasoline. When the suction has increased to the point that the level of the fuel drops below the uppermost opening 28 in the side walls of the sleeve 20 air is admitted at this opening, passes into the annular space 23 between the sleeves 20 and 22, and is drawn up through the small openings 26 around nozzle 24. The action of the air drawn in at this point is to atomize the fuel which is drawn off at the top of the nozzle 24, breaking the same up into a fine spray which then passes up through the nipple 30 and the nozzle 31. I have found that this form of air bleeding is particularly effective as the fuel does not pass up in slugs but in a finely subdivided state. I have found that where the openings 28 are made directly in the side walls of the inner sleeve 22, the action is not nearly so effective as the air entering at that point passes up as bubbles and the fuel is held between bubbles and appears as slugs as it is discharged from the nozzle 24.

As the suction in the nozzle 31 increases more fuel will be drawn out of the accelerating well, this fuel passing down by way of the passages 29 in the head 16 and up through the sleeve 22 and the nozzle 24. If further openings 28 are uncovered the amount of air passing up through the annular space 23 and the passageways 26 is increased until the suction is satisfied and conditions reach an equilibrium.

The compensating air bleed, controlled by the valve 65, extends over a range of positions of the throttle 41 from closed to substantially one-third open. Thereafter the compensating air bleed is closed by the

valve 65 and the air bleed from the accelerating well is depended upon solely.

I do not intend to be limited to the precise details of construction shown and described.

I claim:—

1. In a carburetor having an air inlet, a mixture outlet and a throttle controlling said outlet, a main nozzle, an accelerating well, a connection from said accelerating well to said main nozzle, venting means for admitting air to the upper part of said accelerating well, air venting means for said main nozzle, and means for decreasing the venting of said main nozzle as the throttle opens.
2. In a carburetor, a float chamber, a passage receiving fuel therefrom, two passages

communicating with said first passage, a main nozzle in one of said two passages, the other of said two passages being enlarged intermediate its length, a hollow plug in said enlarged passageway, an idling port receiving fuel from the inner bore of said plug, an annular passage between said plug and the enlarged portion of said passage, said annular passage being closed at both ends by said plug, and lateral passages forming with said annular passage an air-bleeding channel for said main nozzle.

In witness whereof I hereunto subscribe my name this 8th day of February, A. D. 1918.

CHARLES J. GUSTAFSON.
